UNITED STATES PATENT OFFICE

RODERICK W. BRYANT, OF OMAHA, NEBRASKA

DOUBLE SLOPE RE-RAILING FROG

Application filed November 14, 1928. Serial No. 319,243.

The invention relates to rerailing blocks, adapted to be used for replacing the wheels of locomotives and railway cars upon tracks after derailment thereof, and has for its object to provide blocks having channeled members adapted to arch the treads of rails, and provided with upwardly inclined wheel flange engaging surfaces terminating adjacent the inner sides of the rails, whereby the wheel flanges will be positioned where upon further movement of the wheels, the wheel treads will engage the rail treads and the wheel flanges will engage the inner sides of the rails.

15 A further object is to provide the blocks with apertured lugs for the reception of spikes for securing the blocks across ties and the under sides of the blocks with lugs adapted to imbed in the ties for preventing lateral displacement of the blocks.

20 A further object is to proportion the inner sides of the rail arching members, whereby said inner sides will rest upon the bases of the rails for rigidly supporting the rail sides 25 of the blocks and reducing the strain on the rail arching members.

25 A further object is to provide the upper sides of the block with flattened portions on which the wheel flanges rest when they reach 30 the point of re-railment and to provide the central portions of the blocks with shoulders adjacent the flattened portions which, upon movement of the wheels in either direction, will prevent the wheels from going down 35 either incline no matter from which side of the block the wheels have been elevated to re-railment position.

40 A further object is to provide re-railing blocks mounted adjacent rails and having upwardly and inwardly extending wheel receiving channels over which wheels may be moved to re-railing positions from either end of the blocks without changing the blocks, thereby obviating the necessity of providing 45 a plurality of blocks, for instance the type

shown in my Patent No. 1,681,281 issued August 21, 1928, and on which the present invention is an improvement.

With the above and other objects in view the invention resides in the combination and arrangement of parts as hereinafter set forth, shown in the drawings, described and claimed, it being understood that changes in the precise embodiment of the invention may be made within the scope of what is claimed 55 without departing from the spirit of the invention.

In the drawings:

Figure 1 is a top plan view of a section of a railway showing the blocks applied thereto. 60

Figure 2 is an end view of the block shown at the left hand side of Figure 1.

Figure 3 is an end view of the block shown at the right hand side of Figure 1.

Figure 4 is a top plan view of the block 65 shown in Figure 2.

Figure 5 is a side elevation of the block shown in Figure 2.

Figure 6 is a top plan view of the block 70 shown in Figure 3.

Figure 7 is a side elevation of the block shown in Figure 3.

Figure 8 is a vertical transverse sectional view taken on line 8—8 of Figure 5. 75

Figure 9 is a vertical transverse sectional view taken on line 9—9 of Figure 7.

Referring to the drawings, the numeral 1 designates rails and 2 cross ties of the usual construction to which the rails are secured by 80 spikes 3. Disposed adjacent the rails 1 are re-railing blocks 4 and 5, which blocks have their under sides provided with downwardly extending sharpened lugs 6 adapted to imbed in the cross ties for preventing lateral movement of the blocks when in position. The blocks are additionally held against displacement by means of spikes 7 which extend through apertured lugs 8 and into the cross ties. Block 4 is placed to the outside of one 85

80

85

90

of the rails and block 5 to the inside of the other rail.

The blocks 4 and 5 are provided at one side thereof with inverted channeled members 9 which arch the treads of the rails and onto which the wheel flanges are guided by means hereinafter set forth. The blocks 4 and 5 at their sides adjacent the rails engage the rail bases 10 for relieving the strain on the channeled members when the weight of an engine or car is on the blocks.

Referring specifically to the block 4, the opposite ends of said block incline downwardly from the central flat portion 11 and are provided with downwardly inclined flared channels 12 onto which the wheel flanges are forced from either side of the block. As the wheel flanges move upwardly they engage the shoulder 13 of the block and are guided inwardly onto the channel 9, which is a flat surface, and into a position where as the wheel rotates, it will move to a position in engagement with the rail 1 and with its flange engaging the inner side of the rail.

The block 5 is provided with downwardly inclined flared channels 14 into which the wheel rolls according to the direction of movement of the wheel and the wheel is guided toward the adjacent rail 1 by engagement with the flanges 15, and when the wheel reaches the central position, the wheel flange will engage the webs 16 of the blocks and will be in a position where upon movement of the wheel in either direction the tread of the wheel will engage the tread of the rail 1 and the flange of the wheel will engage the inner side of the rail. It will be noted that by providing double ended re-railing blocks, only two blocks will be necessary, and the wheels may be placed on the rails by moving the same in either direction.

From the above it will be seen that re-railing blocks are provided, which may be used for re-railing rolling stock wheels moving in either direction, thereby obviating right and left hand blocks of the single type now in use wherein it will require four blocks. It will also be seen that the side of each block is provided with a channeled member arching the rail in engagement therewith, and that the inner lower edge of the block rests on the rail base thereby positively bracing the block and relieving the strain on the channeled member.

The invention having been set forth what is claimed as new and useful is:—

A double slope re-railing block comprising an elongated body member adapted to be disposed to one side of a rail in engagement therewith, an outward and downwardly extending member carried by the body member and adapted to arch the tread of a rail, upwardly inclined recesses carried by the ends of the body member, whereby wheel flange

guide shoulders are formed for guiding a wheel flange onto the outwardly and downwardly extending member adapted to arch a rail substantially centrally of a rail tread, said recess formed shoulders merging together above the outwardly and downwardly extending rail engaging member at a point substantially centrally of a rail tread beneath the outwardly and downwardly extending member.

In testimony whereof I hereunto affix my signature.

RODERICK W. BRYANT.
